UNITED STATES PATENT OFFICE.

DWIGHT BUSHNELL HENDRYX, OF BRADFORD, PENNSYLVANIA, ASSIGNOR TO HANLEY COMPANY, OF BRADFORD, PENNSYLVANIA, A CORPORATION OF PENNSYLVANIA.

SUPERSTRUCTURE FOR TUNNEL-KILN CARS.

Application filed July 21, 1927. Serial No. 207,441.

My invention consists in the novel features hereinafter described, reference being had to the accompanying drawing which shows one embodiment of the invention selected by me for purposes of illustration, and the said invention is fully disclosed in the following description and claims.

In the operation of tunnel kilns for burning bricks and other coarse clay and ceramic products, the kiln cars are provided with a superstructure, upon which the goods to be fired are supported, to protect the metallic portions of the car from the injurious effects of the high temperatures within the kiln. The superstructure must be provided with passages therethrough for the products of combustion, in order that the lowest rows of goods on the car may be thoroughly and evenly burned, and the superstructure must have sufficient strength to support the great weight, amounting in some cases to many tons, without breaking down when exposed to the highest temperatures. Heretofore these structures have usually been made of fire clay or other highly refractory material in special shapes which were costly, and required a kiln owner to keep a large supply of the necessary shapes on hand for repairs and replacements. The object of my invention is to greatly cheapen the cost of construction of the superstructure, by employing between courses of simple rectangular forms of refractory material, courses of brick of standard size made either of refractory material or preferably being standard ordinary bricks, such as the product of the kiln, the courses being combined in such manner as to provide the great strength required, and the necessary passages for the products of combustion and flue gases, hot air, etc., to facilitate the operations taking place in the kiln.

In the drawings:

Fig. 1 represents a side elevation of a tunnel kiln car embodying my invention.

Fig. 2 is an end view of the same.

Fig. 3 is a horizontal section on line 3—3 of Fig. 1.

In the drawings, 1, represents the metal car body, and 2, the supporting wheels. The metal body is preferably provided with a layer, illustrated at 3, of refractory material applied in any desired way and made up of block or otherwise, the edges of which project, as at 4, beneath the longitudinal

projecting ribs on the walls of the tunnel, and suitable sand or other seals (not shown) may be provided, if desired, to prevent direct radiation to the metal parts of the car and to prevent the hot gases from circulating below the same, as far as possible.

Upon the base layer, 3, I arrange a horizontal layer of refractory blocks, indicated at 5, which are of oblong shape, of greater width than the length of a standard brick, and of greater length than the width of several standard bricks. The sides and ends of the blocks, 5, are brought together closely at their meeting faces, to produce a substantially uniform supporting surface.

Upon this layer of blocks are laid double rows of standard size bricks with their faces of greatest area horizontal, as indicated at 7—7, two pairs of bricks, 7, being laid upon each block, 5, spaced from each other, as indicated at 8, and having their outer edges set back from the ends of the blocks, 5, as indicated at 9—9, and their ends set in from the edges of the blocks, 5, as indicated at 10, 10. A course of the rectangular blocks, like the blocks, 5, are then placed upon the bricks, 7, as indicated at 5^a, 5^a, and each block, 5^a, of the upper course will be thoroughly supported by the flat laid bricks, 7, while spaces, 8^a and 9^a, extending transversely of the car, and narrower spaces, 10^a, extending longitudinally of the car, are formed between the spaced pairs of bricks, as clearly shown in the drawings. This arrangement permits the kiln gases to circulate beneath the top course of refractory blocks, and heat them so that an even and thorough burning will be imparted to the ware placed immediately above the superstructure.

While the bricks, 7, of refractory material and of standard size could be used, we find that ordinary standard bricks give entirely satisfactory results, and result in greater economy, and an ample supply is always at hand. It is, therefore, only necessary to use and stock for repairs, a supply of the refractory blocks, of a single size for both the top and lower courses, so that the blocks (5 and 5^a) are interchangeable in these courses. According to my construction great strength is obtained, as the blocks, 5^a, of the upper course are each supported by the bricks, 7, placed with their faces of greatest area horizontal, and are supported over a wide area adjacent to each end and

sufficiently toward the center so that they are not liable to bend or break under strain.

While I might employ a single flat course of separated standard bricks, 7, between the 5 courses of refractory blocks, I prefer to employ two courses, as the construction is equally strong and affords larger spaces for the passage of heated gases through beneath the upper course of refractory blocks, with 10 better results in preheating, firing and cooling.

The passages, 8^a, 9^a and 10^a, also assist in cooling the ware uniformly by facilitating the cooling of the lower course or courses, 15 while the cars are passing through the cooling zone of the kiln, and after the cars are removed from the kiln.

What I claim and desire to secure by Letters Patent is:—

- 20 1. A tunnel kiln car having a superstructure comprising a course of blocks of refractory material, supported upon blocks of standard brick size.
- 25 2. A tunnel kiln car having a superstructure comprising a course of blocks of refractory material, supported upon blocks of standard brick size spaced apart to provide passages for the circulation of gaseous products beneath the said blocks.
- 30 3. A tunnel kiln car having a superstructure comprising a course of blocks of re-

fractory material, supported upon blocks of standard brick size, each block being superimposed upon two of said bricks, placed with their faces of greater area horizontal, and separated from each other, and from the ends of the blocks to provide transverse passages below said blocks. 35

4. A tunnel kiln car having a superstructure comprising a course of blocks of refractory material, supported upon blocks of standard brick size, arranged in pairs one above the other with their faces of greatest area horizontal, each block being supported upon two pairs of standard brick size blocks, separated from each other and from the ends and lateral edges of the blocks, to provide transverse and longitudinal passages below said blocks. 40

5. A tunnel kiln car, having a superstructure comprising a course of rectangular refractory blocks, superimposed courses of standard size bricks arranged in pairs with their faces of greatest area horizontal, said pairs being separated from each other and set in from the edges of said blocks, and a top course of refractory blocks supported upon said bricks and registering substantially with the blocks of the lower course. 45 55

In testimony whereof I affix my signature. 60
